UNITED STATES PATENT OFFICE.

WILLIAM LEWIS, OF UTICA, NEW YORK.

WIRE MATTRESS.

1,225,258.

Specification of Letters Patent.

Patented May 8, 1917.

Application filed April 9, 1915. Serial No. 20,249.

To all whom it may concern:

Be it known that I, WILLIAM LEWIS, a citizen of the United States, and a resident of Utica, in the county of Oneida, in the 5 State of New York, have invented new and useful Improvements in Wire Mattresses, of which the following, taken in connection with the accompanying drawings, is a full, clear, and exact description.

10 This invention relates to certain improvements in wire mattresses of the spring, woven wire or link bar type, in which there is always more or less liability of excessive stretching and consequent sagging or contracting of the central portions of the longitudinal edges by reason of the excessive use and pressure to which these portions of the mattress are ordinarily subjected.

15

The main object of my present invention 20 is to obviate these objectionable results by providing simple and comparatively inexpensive bracing devices which may be permanently or detachably applied wherever necessary, to the longitudinal edges and adjacent portions of the main body of the mattress in such manner that the stresses upon the edges will be distributed to the main body, without in any way affecting the general resiliency or flexibility of the mattress.

25 Another object is to provide these bracing members with upstanding guards for retaining the superposed upholstered mattress in operative position upon the wire mattress against lateral displacement.

Fig. 7 is an edge view of the same mattress.

Fig. 8 is an enlarged transverse vertical section view, taken on line 8—8, Fig. 7. 60

Fig. 9 is a perspective view of one of the detached reinforcing members shown in Fig. 6.

Fig. 10 is a top plan, partly broken away, of a coil spring mattress and reinforcing 65 members for the longitudinal edges thereof incorporated therein.

Fig. 11 is an edge view of the same mattress.

Fig. 12 is a transverse vertical sectional 70 view, taken on line 12—12, Fig. 11.

The mattress shown in Figs. 1 to 4, inclusive, comprises a woven wire fabric —1— which is stretched in any well known manner between end bars —2— connecting the 75 opposite ends of side rails —3—, the longitudinal edges of the woven wire fabric —1— being reinforced at intervals throughout its length, and particularly at the intermediate portions, by U-shaped braces —4— incorporated therein, in a manner presently 80 described.

For convenience and economy, these braces are made of wire of suitable gage, each brace being provided with similar parallel 85 arms —5— arranged in spaced relation and united at one end by an upwardly arched cross bar —6—.

The arms —5— serve as reinforcing members for the longitudinal edges of the woven 90

members thereto, the same locking rods being of sufficient length to retain all of the reinforcing members which may be in alignment therewith throughout the length of the 5 mattress.

Upon reference to Fig. 3, it will be seen that the arms extend transversely and in close proximity to the undersides of a relatively large number of the interlocked wire 10 coils of the fabric, so that any pressure which may be brought to bear upon the longitudinal edges of the fabric will be transmitted not only to all the coils intervening between the loops —7—, but also to the 15 central portion of the fabric, and that as soon as this pressure is relieved the reinforcing members operate to restore said edges to their normal positions in substantially straight lines.

By spacing the lengthwise arms of these reinforcing members a considerable distance apart, it is evident that only a small number will be required to reinforce such portions of the longitudinal edges of the fabric as 20 may tend to become deformed by continued use, and, furthermore, by incorporating these reinforcing members in the fabric and supporting them wholly thereby preserves the flexibility and resiliency of the mattress, as 25 well as the form, the locking bars —8— being also made of wire and, therefore, more or less resilient and flexible, but still sufficiently strong to assist the reinforcing members —4— in preserving the edges of the 30 woven wire in their original form, or rather in preventing the sagging or contracting of such edges.

In addition to the function of the up-standing arches —6—, they may also serve 40 as supports for lengthwise guard rails —9— which are clamped thereto by clips —10— so as to hold the edges of the bedding against undue flattening or matting throughout their lengths.

In practice, I have found that two of the loops —7— on each of the arms —5—, one 45 near each end, is sufficient for the purpose, the outer loops being close to the arched cross bar —6— for interlocking engagement with the outermost coil of the fabric, while the inner loops are interlocked with one of the longitudinal coils of the main body some 50 distance inwardly from the longitudinal edge so as to distribute any strains which may be applied to said edge over a relatively wide area of the mattress and thereby 55 maintain such edges against deformation.

It is now clear that these reinforcing members —4— may be easily and quickly 60 applied to or removed from any old or new woven wire mattress. That is, they may be used for restoring the deformed edges of an old mattress, or for maintaining the longitudinal edges of a new mattress in their original 65 straight lines, without in any way di-

minishing the flexibility or resiliency of the mattress as a whole. For example: If it is desired to remove these reinforcements at any time, it is simply necessary to withdraw the rods —8— endwise from the loops and 70 coils through which they are inserted, thus freeing the reinforcing members and allowing them to be withdrawn downwardly and laterally, either in combinations as connected by the rail —9— or individually if 75 the rail is not employed.

In Figs. 6 to 9, inclusive, I have shown a slightly modified reinforcing member —4'— as used in connection with what is commonly termed a link bar and plate mattress 80 —20— supported in any well known manner upon a frame —21—, the reinforcing members —4'— being substantially like that shown in Figs. 1 to 5, inclusive, except that the loops as —5'— at their inner ends are 85 closed upon locking bars as —8'— constituting portions of the mattress —20—, thereby permanently securing the reinforcing members to said mattress but otherwise the application is similar to that previously described for the woven wire mattress shown in Fig. 1.

In Figs. 10, 11 and 12, the reinforcing member shown in Fig. 5 is used in connection with the longitudinal edges of a helical 95 spring mattress —30— in which the lower ends of the springs are supported upon suitable bars —31— while the upper ends of the marginal series are connected to a marginal frame —32— running around the longitudinal edges and ends of the mattress, it being understood that the remaining springs of the system may be tied together in any well known manner, as for example by lengthwise tie-bars —33— and cross bars —34—. 100

In applying the reinforcing member —4— to this particular type of mattress, the longitudinal members of the marginal frame —32— are placed in the recesses between the upwardly arched members —6— and adjacent loops —7— as shown more clearly in Fig. 12, the remaining portions of the opposite arms —5— of the reinforcing member being extended transversely of the upper portion of the mattress and the inner loops —7— passed upwardly between the cross bar —34— for receiving the lengthwise locking bars —8— which are arched to rest upon the upper faces of the cross bars to retain the reinforcing members in operative 110 position, and at the same time permitting the locking bars —8— to be passed through said loops in attaching the reinforcing members to the mattress or in removing them therefrom. 115

What I claim is:

1. The combination with a wire mattress, of reinforcing means for the edges thereof comprising cross bars having loops inserted into the mattress from one side, and a rod 120

slidable through a portion of the mattress and through said loops for detachably locking the bar and rod to each other and to the mattress.

5 2. The combination with a wire mattress, of reinforcing means for the edges thereof comprising a U-shape bar having its opposite arms provided with loops inserted into the mattress from the underside and a rod 10 slidable through a portion of the mattress and through the loops for detachably locking the bar and rod to each other and to the mattress.

15 3. The combination with a wire mattress, of reinforcing means for the edges thereof comprising a U-shape bar having its opposite arms extending transversely from one edge of and under the mattress and each provided with a pair of loops for insertion 20 into a portion of the mattress, and separate rods slidably interlocked with portions of the mattress and with said loops.

25 4. In combination with a wire mattress, reinforcing members extending inwardly from one edge part way across said mattress and attached thereto at points near the edge and at other points some distance in-

wardly therefrom, the outer edges of said reinforcing members being provided with upwardly arched portions extending some 30 distance above the plane of the mattress to retain the bedding thereon, and a guard rail attached to the apexes of the arched portions and extending along the edge of the mattress.

35

5. A reinforcing device for the longitudinal edges of wire mattresses consisting of a U-shape bar of wire having substantially parallel arms extending part way across the mattress from one edge and provided with 40 loops for engaging said edge and with additional loops some distance inwardly from the first named loops for engaging other portions of the mattress, and locking wires passed through said loops and incorporated 45 in the mattress to retain the reinforcing members in operative position.

In witness whereof I have hereunto set my hand this 5th day of April, 1915.

WILLIAM LEWIS.
